UNITED STATES PATENT OFFICE.

TRUSTIN C. HICKS, OF PITTSBURGH, PENNSYLVANIA.

HAND DISHWASHING MACHINE.

Application filed November 15, 1921. Serial No. 515,374.

To all whom it may concern:

Be it known that I, TRUSTIN C. HICKS, a citizen of the United States, residing at Pittsburgh, in the county of Allegheny and 5 State of Pennsylvania, have invented new and useful Improvements in Hand Dish-washing Machines, of which the following is a specification.

This invention relates to dish-washing machines, and more particularly to a machine which is specially adapted for supporting the dishes and similar articles in such manner as to permit the same to be acted upon to the best advantage by a spray 15 of washing fluid.

One of the main objects of the invention is to provide a device of the character stated of very simple construction which may be readily produced and sold at relatively 20 small cost. A further object is to provide means for supporting plates and similar articles of chinaware at such an inclination as to be readily acted upon by the spray streams, this supporting means being 25 adapted to accommodate plates and similar articles of varying sizes. A further object is to provide means for supporting cups, bowls, and similar articles in an inverted position at such an inclination as to permit 30 the same to be readily acted upon from beneath, as well as above, by the spray streams for effectually removing all foreign materials. Further objects will appear from the detailed description.

35 In the drawings:—

Figure 1 is a front view of the washer;
Figure 2 is a top plan view;

Figure 3 is a section taken substantially on line 3—3 of Fig. 2;

40 Figure 4 is a section taken substantially on line 4—4 of Fig. 2;

Figure 5 is an underneath view of the sprayer and associated parts which I prefer to use in connection with my machine.

45 The machine includes a boxlike casing 1 of sheet metal which is supported by feet 2 of angle cross-section. At one end of the casing 1 I provide a top plate 3 which cooperates with the front and back walls 4 and 50 5, and the adjacent end wall to form an enclosing hood 6 open at its inner side. Within this hood, at each end thereof, are secured two angle brackets 7 which are inclined upwardly and inwardly of the casing and are 55 disposed at an angle of 45° to end wall 8.

A supporting member or shelf 9 of reticulated construction is supported by each pair of brackets 7 and extends transversely of the casing 1. These shelves serve to support cups, glasses, and similar articles in an inverted position and inclined at an angle of 45° so as to permit ready washing of the same by a spray member inserted into the casing and moved about so as to direct a spray onto the articles to be washed. In 60 this connection, I have found by extensive experiments that an angle of approximately 45° is the most effective angle at which the shelves 9 can be supported. During the washing operation of the articles upon the 65 shelves, the hood 6 serves to effectually prevent splashing of the water or washing solution outside of the casing 1.

To permit ready manipulation of the sprayer, front wall 4 of casing 1 is cut away 70 from its upper edge to provide an opening 10 by means of which the sprayer can be readily inserted into the casing and manipulated so as to direct the spray upon the articles to be washed. At the opposite end 75 of casing 1 from shelves 9 I provide a rack 11 for supporting plates, saucers, and similar articles. This rack includes substantially U-shaped end frames 12 which are connected by brace bars 13, each of these frames 80 having the lower end of its end arm 13 turned inwardly to provide a foot 14. For supporting the plates and similar articles on edge 85 I provide a plurality of spaced parallel coils 15 of wire or other suitable material, these coils being secured to the rack 11 and the convolutions of the coils being spaced a comparatively great distance apart. These coils provide simple and efficient means 90 whereby the plates and similar articles may be readily supported on edge at an inclination transversely of casing 1 and also at an inclination to the vertical, so as to be acted upon to the very best advantage by a spray 95 directed onto the plates from a sprayer inserted into casing 1 through opening 10. Also, the coils 15 will readily accommodate plates and similar articles of unusual size by placing the plate at a considerable 100 inclination transversely of casing 1, this being possible due to the provision of the coil members the convolutions of which are spaced apart, as previously described. A cylindrical container 16 of woven wire construction is placed in casing 1 adjacent to 105 110

the inner end of rack 11. This container is adapted to receive knives, forks, spoons and similar articles to be washed.

Bottom 17 of casing 1 is provided with a central longitudinally extending trough 18, and with discharge openings 19 communicating with this trough adjacent to each end of the casing. Opening 19 discharges into a downwardly and outwardly inclined discharge spout 20 secured to the underface of the bottom of the casing. In practice, the casing 1 is placed upon a draining board adjacent to a sink, so as to be inclined downwardly toward the sink, and the upper opening 19 is closed by a suitable stopper or plug. During the washing operation, the washing solution and the particles of food etc., removed from the dishes flows into trough 18 and is discharged through opening 19 and spout 20 into the sink. After the dishes have been washed by means of a soap or other suitable solution sprayed onto the same, they may be readily rinsed by spraying hot water onto the dishes, after which they can be either wiped by hand or permitted to set in casing 1 until they have dried.

I prefer to use a sprayer, such as that illustrated in Figure 5, which is provided with a body 21 for reception of a suitable detergent, this body being provided at one end with a neck 22 for reception of a suitable hose 23 provided with a connector 24 of any suitable or preferred type by means of which the sprayer may be connected to a faucet. At its other end body 21 is provided with a spray-head 25 having a plurality of spray openings 26 which are directed radially of the head and are disposed in alignment axially thereof. The body 21 is closed by a suitable plug 27, or in any other suitable or preferred manner, so as to permit ready introduction of the detergent into the body. As will be understood, the sprayer operates within casing 1, through opening 10, the spray head 32 being moved about so as to direct the washing solution over the articles to be washed to the best advantage. By

turning the sprayer so as to direct the spray beneath shelves 9 the cups and other hollow articles placed upon these shelves may be readily washed. The casing 1 is so constructed, and the shelves 9 and rack 11 are so arranged, as to permit the spray to be readily directed beneath the shelves, the inclination of the shelves being such that the lower shelf does not interfere in any way with directing the spray beneath the upper shelf and into the cups and other articles supported thereby.

The machine constructed in the manner above described and illustrated has been found by extensive experiments to be highly efficient, and can be readily produced and sold at small cost, being specially adapted for use in the average household.

What I claim is:—

1. In a device of the character described, a casing open at its top and constructed at one end to form a hood opening into the casing, said casing having one wall cut away so as to permit a spraying device to be introduced into and manipulated within the casing, means within the hood for supporting cups and other open articles, said means being of open construction, and means remote from said supporting means for supporting dishes and similar articles to be acted upon by a spray, the last mentioned means being of open-work construction, said casing being provided with outlet openings.

2. In a device of the character described, a casing open at its top and constructed at one end to form a hood, shelves of reticulated construction supported within the hood and disposed at an upward and inward inclination relative to the casing, and a rack adapted to support plates and similar articles in position to be acted upon by a spray, the front wall of the casing being cut away to permit a spraying member to be introduced into and manipulated within the casing.

In testimony whereof I affix my signature.

TRUSTIN C. HICKS.
